SUPPORT STRUCTURE FOR SCREENING CYLINDERS

George W. Borton, Philadelphia, Pa.

Application September 9, 1949, Serial No. 114,766

6 Claims. (Cl. 241—91)

1

This invention relates to crushing machinery and more particularly to crushing machinery of the Bradford mill type having a rotating cylindrical screen for discharging the crushed material.

An object of this invention is to provide a rotating crushing machine which is more easily constructed and less expensive to build.

Another object is to provide a crushing machine that is more efficient to operate.

A still further object is to provide a crushing machine of improved performance and durability.

Further objects of the invention will appear from the following specification taken in connection with the accompanying drawings in which:

Figure 1 is a side view of the crushing machine with parts in section;

Figure 2 is an end elevational view of the discharge end of the crushing machine along lines 2—2 of Figure 1;

Figure 3 is an end elevational view of the feed end of the crushing machine along lines 3—3 of Figure 1;

Figure 4 is a detailed sectional view of the feeding end bearing;

Figure 5 is a detailed sectional view of the discharge end bearing;

Figure 6 is a longitudinal sectional view of a portion of the machine as taken along the line 6—6 of Figure 3;

Figure 7 is a cross-sectional view as taken along the line 7—7 of Figure 6;

Figure 8 is a fragmentary perspective view of the interconnected parts shown in Figures 6 and 7;

Fig. 9 is a fragmentary sectional view of another embodiment; and

Fig. 10 is a cross sectional view along lines 10—10 of Fig. 9.

Referring to Figs. 1 to 8 of the drawings, there is shown a crushing machine comprising a cylindrical drum 10 mounted between two bearings 12, 13. The bearings 12, 13 are supported by the stationary cross beams 14, 15 respectively. The drum is rotated in the bearings 12, 13 by a pulley or gear 16. The material is fed to the rotating drum by a chute (not shown) centrally through the opening 19 of the flange or hub 40 of the feed annulus 25. It passes freely along the axis to the conical portion 39 of the annulus and is passed on and moved longitudinally through the drum 10 by the deflector blades 20 or angular setting of lifting shelves as the material is picked up and dropped and broken up to pass through the apertures 21 of the drum. The larger unbroken pieces are 55

removed to the discharge end of the drum and may be discharged in any desired manner as by a plow and through an opening 38 in the discharge spider 26.

The drum 10 is mounted at the ends in the bearings 12, 13 by the feed annulus 25 and the opposite spider 26 respectively. The annulus and spider are structurally connected by the longitudinal I- or H-beams 27.

The annulus 25 has an inwardly directed flange 28 with pads 22 for bolting to the ends of the beams 27. Similarly, the spider 26 has the flange 29 with pads 23 for the other ends of the beams 27. These flanges are in arcuate form as illustrated in Fig. 8 and usually the ends of the I-beams at the cooperating surfaces will be ground to fit the surfaces of the pads 22, 23 or an intervening spacer or shim 30 may be interposed between the I-beam and the flange as illustrated.

As illustrated in Figs. 1 to 8, the perforated cylinder 32 of the drum is between the inner edges of flanges 28, 29 at its ends and the beams 27 are bolted to the pads 22, 23 on the flanges and engage and support the outer surface of the perforated cylinder strips 32, the bolts 34 passing through holes in the flange members penetrated.

This construction with the annulus 25 provides a free feed opening 19 unobstructed by spokes of a spider or other supporting means, while the beams 27 rigidly brace the drum from end to end and securely support the load within the perforated plates or cylinder 32 retained by these beams against outward warping.

The pads 22, 23 of the flanges 28, 29 are strongly bound to the beams 27 and the cylinder parts by the bolts 34 so that the entire drum structure with its annulus 25 and spider 26 is self-supporting, these parts cooperating to rotatably carry the load between the end bearings 12, 13.

Preferably the bearing 12 (Figs. 1 and 4) at the feed end is constructed to take radial and axial thrust retaining the drum in place longitudinally. The other bearing 13 (Fig. 5) may be of any desired structure and is preferably radial permitting relative axial shifting of the parts.

The bearing structure 12 surrounds the hub 40 extending forward from the cone 39 of the annulus 25 and comprises a radial weight-supporting bearing 41, and a combined radial and axial bearing 42 with dust seals 43, 44 at each end.

The outer ring 45 is mounted on the cross beams 14 and rigidly secured thereto in any desired manner. The bearing 13 for the spider 26 is mounted in block 50 on cross beam 15 and comprises a ring 51 and cap bearing 52 with bushing 53, race

54, and a lock washer 55.

The bearing structure 13 surrounds the hub 40 extending forward from the cone 39 of the annulus 25 and comprises a radial weight-supporting bearing 41, and a combined radial and axial bearing 42 with dust seals 43, 44 at each end.

The outer ring 45 is mounted on the cross beams 14 and rigidly secured thereto in any desired manner. The bearing 13 for the spider 26 is mounted in block 50 on cross beam 15 and comprises a ring 51 and cap bearing 52 with bushing 53, race

54, and a lock washer 55.

The bearing structure 13 surrounds the hub 40 extending forward from the cone 39 of the annulus 25 and comprises a radial weight-supporting bearing 41, and a combined radial and axial bearing 42 with dust seals 43, 44 at each end.

The outer ring 45 is mounted on the cross beams 14 and rigidly secured thereto in any desired manner. The bearing 13 for the spider 26 is mounted in block 50 on cross beam 15 and comprises a ring 51 and cap bearing 52 with bushing 53, race

ring 54, rollers 55 and retainer 56. Seal 58 is provided between the bushings 53 and ring 51.

These bearing structures 12, 13 reduce the frictional resistance and at the same time provide secure support for the drum. They are dust sealed and durable in service and contribute to the performance and economy of the mill in service.

A different structure of the mill (Figs. 9 and 10) positions the beams 57 within the flanges 28, 29 of the drum heads 25, 26, the beams being bolted to the seat pads 33 as at 64 and with the cylinder plates 62 separately bolted to the inner bases 61 of the beams as indicated at 65. This construction maintains the strength and rigidity of the drum but with reduction in the diameter of the crushing chamber.

In both forms of the mill the material feed is central into the drum and there is no engagement of material with spider arms and this avoids the continuous end thrust of the ribbon of coal or other material being fed, and reduces the resultant wear on the parts. The inner surfaces of the perforated cylinder are clear for rolling treatment of the particles and fragments with only such shelving, blading, etc., as is desired for the lifting and progress of the material in passing into and through the mill. The formation of the entrance annulus with the axially extending hub 40 and flange 28, and the intermediate conical portion 39 gives a very strong and stiff structure for attachment of the beam ends in a combination exceptionally rigid and most efficiently applying the metal to the carrying of the load. At the same time the crushing action is effective and controllable by the material handling equipment positioned within the drum in any desired arrangement depending on the particular material and the treatment involved.

I claim:

1. In a crushing mill of the rotary type having a screening cylinder and circular heads at the feed and at the discharge ends of said cylinder, a feed end head in the form of an annular member having parallel circular flanges at its inner and outer peripheral edges, said flanges extending axially of said cylinder, the central opening of said annular member providing an unobstructed feeding aperture for said cylinder and the flange thereof defining said opening, providing means for rotatably supporting the feed end of said cylinder, a discharge end head in the form of a circular member having a circular flange extending from its peripheral edge in coaxial alignment with the outer flange of said feed end head, and circumferentially spaced beams extending between and secured to corresponding peripheral surfaces of said aligned flanges, said beams extending parallel to the axis of and providing supporting means for said cylinder.

2. A crushing mill as set forth in claim 1, in which said beams are adapted to be secured to either of the opposed peripheral surfaces of each

of said aligned flanges, and in which said beams are adapted to provide supporting means for different diameter cylinders.

3. In a crushing mill of the rotary type having a screening cylinder and circular heads at the feed and at the discharge ends of said cylinder, a feed end head in the form of an annular member of hollow truncated conical shape having parallel circular flanges at its inner and outer peripheral edges, said flanges being coaxial with said cylinder, the central opening of said member providing an unobstructed feeding aperture for said cylinder and the flange thereof defining said opening providing means for rotatably supporting the feed end of said cylinder, a discharge end head in the form of a centrally bored spider having a circular peripheral flange extending from its outer peripheral edge in coaxial alignment with the outer flange of said feed end head member, and circumferentially spaced beams extending between and secured to the peripheral surfaces of said aligned flanges, said beams extending parallel to the axis of and providing supporting means for said cylinder.

25 4. A crushing mill as set forth in claim 3 in which said beams are of I-beam shape and in which each of the opposed peripheral surfaces of each of said aligned flanges is adapted to have secured thereto corresponding horizontal flanges 30 of said I-beams and in which said I-beams are adapted to provide supporting means for different diameter cylinders.

5. A crushing mill as set forth in claim 3 in which said beams are of I-beam shape, having corresponding flanges adapted to be secured to the outer peripheral surfaces of said aligned flanges and in which said cylinder is secured to said horizontal flanges of said I-beam, said cylinder being of a diameter substantially equal to 40 the outside diameters of said heads.

6. A crushing mill as set forth in claim 3 in which said beams are of I-beam shape having corresponding flanges adapted to be secured to the inner peripheral surfaces of said aligned flanges and in which said cylinder is secured to the opposed horizontal flanges of said I-beams, said cylinder being of a diameter substantially less than the outside diameters of said heads.

GEORGE W. BORTON.
